UNITED STATES PATENT OFFICE.

ARON MILLS BEAM, OF DENVER, COLORADO; LEROY J. BEAM ADMINISTRATOR OF SAID
ARON MILLS BEAM, DECEASED.

CONTINUOUSLY-OPERATING ORE OR ORE-SHALE CONVERTING RETORT FURNACE.

Application filed February 26, 1924. Serial No. 695,265.

My invention relates to a new and improved continuously operating ore and oil shale converting retort furnace.

And the objects of my invention are:

- 5 First: to provide an ore and oil-shale converting retort, that continuously feeds ore or oil-shale through it and applies to the ore or oil-shale a radiated, and also an indirect, and also a muffled heat to the ore or oil-shale and converts the oil-shale to a condition which enables the oil and other valuable products in it to be recovered by inexpensive precipitation and other treatments.
- 10 Second: to provide a new and improved continuously operating ore or oil-shale converting retort-furnace in which two ore or oil-shale roast-converting muffled retorts are placed one above the other, the lower retort of which rests on brick walls and is placed directly above a fuel burning fire-box or combustion chamber, and receives its ore or oil-shale converting heat from the flame and hot gases of combustion that flow from the fire-box and the combustion chamber which flow directly against the bottom side of the lowest retort, and the heat therefrom penetrates through the floor of this lower retort into the ore or oil-shale moving along its bottom through it and thus converts the ore or oil-shale by the application of a radiated or indirect and a muffled heat of low degree F., while the retort above this lowest retort is provided with heat that flows directly from the combustion chamber to its under side through by-pass flues that extend from the opposite sides of the rear end of the combustion chamber and convey the heat around and up past the lower retort and discharges it into a cast iron flue place above and between the top of the lowest retort and the bottom of the upper retort and from the opposite end of this upper retort from its heat entering end, by-pass flues are placed around the upper retort that convey the heat to a cast iron flue above this upper retort that conveys the heat and gases of combustion to a chimney at the rear end of this upper flue and to provide a new ore and oil-shale feeding machine at the side of the chimney and a chute that conveys the crushed ore or oil-shale past the rear end of the upper flue and discharges it into the upper retort, and to provide a continuously forwardly moving endless ore and oil-shale conveyor arranged through both retorts to move the ore or oil-

shales continuously by a constant, unbroken forward movement through both retorts.

Third: to provide a continuously and automatically operating oil-shale converting multiple roasting floor retort furnace that 60 operates to convert ores or oil-shales by radiated or muffled heat, and to provide such a retort furnace made up of two independently separated and replaceable sections and with flue members made in movable and separable sections between the two retorts, and also one above the upper retort, said retorts and flues being clampably bolted together into a practically air-tight retort furnace, and to provide means for feeding crushed and dried ores or oil-shales into 70 said retorts and for moving them with a stirring and rabbling action with a continuously forward movement through said retorts.

Fourth: to provide a multiple roasting floor ore or oil-shale retort furnace, that is provided with an automatically and continuously operating variable speed and an automatically tightening ore or oil-shale feeding conveyor that is arranged and adapted to 80 feed crushed and dried ores or oil-shales through my multiple retort furnace.

Fifth: to provide an ore or oil-shale multiple retort furnace that is simple in arrangement, inexpensive to construct and operate, and economically successful in the treatment of ores or of oil-shales, and that can be quickly and inexpensively erected in mining districts, and the parts of which can be easily removed and replaced during the 90 operation of the furnace.

I attain these objects by the mechanism illustrated in the accompanying drawings, in which:

Figure 1 is a sectional side elevation of 95 my ore and oil-shale converting retort through the longitudinal center of it on line 2—2 of Figure 2.

Figure 2 is a plan view of Figure 1.

Figure 3 is a side view—slightly enlarged—of the two end portions.

Figure 4 is an end view of the feed end of the furnace.

Figure 5 is a transverse sectional view thereof on the line 5—5 of Figure 3.

Figure 6 is a view of the opposite end of the furnace from that shown in Figure 4.

Figure 7 is a transverse sectional view on the line 7—7 of Figure 3.

Figure 8 is a longitudinal sectional view 110

through a portion of one of the retorts and the conveyor mounted therein.

Figure 9 is a plan view of the portion of the conveyor shown in Figure 8, the side wall of the retort being shown in section.

Figures 10 and 11 are perspective views of the opposite ends of a retort section, showing the manner in which the ends of the adjoining sections fit together.

10 Figure 12 is a vertical sectional view showing the two ends of the retort sections as they appear when connected.

Figure 13 is a transverse sectional view of a retort furnace adapted for the treatment 15 of oil shale.

Figure 14 is a side view of a portion of the arrangement shown in Figure 13.

Figures 15, 16, and 17 are sectional views, respectively, on the lines 15-15, 16-16, 20 and 17-17 of Figure 13.

Figure 18 is a diagrammatic plan view, on a reduced scale, of the character of furnace shown in Figure 13.

Figure 19 is a diagrammatic elevation, 25 showing the manner of conveying the gas from the retorts to water-holding tanks, for the separation of the oil from the said gas; and

Figure 20 is a transverse sectional view 30 through one of the retorts and the adjoining flue, and showing the manner of closing the gas outlet in said flue with a manually operated damper.

Figure 21 is a side view of a portion of one 35 of the shaft supporting brackets on the front end of the machine showing an adjustable shaft bearing a box mounted therein.

Similar reference numerals refer to similar parts throughout the several views.

40 Referring to the drawings:

My new complex, refractory and rebellious ore, and oil shale, low-heat roast-converting multiple-retort furnace consists of preferably only two retorts 1 and 2, placed one 45 above the other in vertical alignment; but more than two retorts can be used one above the other in a single furnace where a very large tonnage capacity is required. These two retorts 1 and 2 are encased and supported in and on walls of brick or concrete, fire-brick and fire-clay slabs, or cement being used to protect the bottom of the lower retort 2. These enclosing and supporting walls consist of the opposite side walls 3 50 and 4, and the front end wall 5 and the rear end wall 6, and the inside surfaces of these walls are preferably faced with fire-brick. A fire box and combustion chamber 7 is formed between the walls 3 and 4 and the 55 front end wall 5.

This fire box 7 comprises the combustion chamber above the grate bars and it has an ash pit space below the grate bars, and it is formed by a bridge wall 9, between walls 60 3 and 4, and grate bars 10, which are sup-

ported between and by the bridge wall and the front end wall 5, and it has a front frame 11, which is secured to the outside surface of the wall 5.

The door frame 11 is provided with doors 70 11^A, opening into the combustion chamber above the grate bars, and with doors 11^B that open into the ash pit space below the grate bars.

The under side 8 of the bottom of the retort 2 is covered with fire clay slabs or fire clay cement 9^A, as desired, for about two-thirds of the length, in order to prevent the heat from the combustion chamber from blistering or warping it. 75

The products of combustion, which are flames, hot gases and smoke of the combustion chamber, flow up against the fire clay slabs 9^A that are placed under and against the bottom of the retort, and they flow along 80 the under side of the fire clay slab covered bottom of the retort 2, and along and against its uncovered rear end, and then they flow into two by-pass flues 12, the

bottom of the retort 2, and along and against its uncovered rear end, and then they flow into two by-pass flues 12, the 85 lower ends of which are built into the brick side walls, and they extend up around the outside surfaces of the retort 2, and into a flue 13. These by-pass flues 12 consist of

cast iron pipes that have inwardly projecting lower and upper ends 12^A and 12^B, the 90 ends 12^A of which are built into the brick side walls 3 and 4, and they extend outside of the brick walls and up, around and past the retort 2, and their upper ends 12^B enter

apertures 12^C formed in the opposite sides 95 of the cast iron flue casting 13, to which they are bolted. The flue casting 13 rests on top of the retort 2, between it and the upper retort 1, and hot gases and smoke flow through this flue 13 against the bottom of

the retort 1 to its opposite end where they enter another pair of by-pass flues 14, which 100 are bolted to apertures 13^A formed in the opposite sides of the flue 13 at their lower ends, and these two by-pass flues 14 extend up and around the outside of the retort 1 and their upper ends enter into apertures

14^A formed in the opposite sides of a cast-iron flue 15, to which they are bolted. The flue 15 is placed on top of the retort 1, and the hot gases and smoke flow through it to a flanged outlet 15^A to which a smoke stack 15^B is secured. 105

These two retorts 1 and 2, and their flues 13 and 15, rest on the brick walls 3, 4, 5 and 6; they are not, however, covered or enclosed with brick as most ore treating retorts are, but they are exposed fully to view and to the atmosphere on all sides. 110

My preferred detail construction of the retort 2 and of the flue 13, and of the retort 1 and the flue 15, is as follows: 115

These two retorts 1 and 2 are constructed in the form of long tunnel members, and they are preferably constructed of cast iron 120

castings, but can be made of any other suitable material or materials; and to enable them to be easily and quickly handled in constructing them and in erecting them 5 into retort furnaces, I make them in short cast iron sections that are bolted or otherwise secured together in end to end alignment. The lower retort consists of a floor member 16 which is provided with wall resting lugs 16^A, that rests on top of the side

10 walls 3 and 4, and also consists of a cap member, which cap member consists of a channel member having a web or roof portion 17 and two opposite flanges or down-

15 wardly extending side portions 18, which bear on the wall resting lugs 16^A.

The floor member 16 of this retort 2 receives and convertingly roasts the crushed ore and oil shale that is moved over its 20 upper surface, and it consists of a flat cast iron plate, the opposite sides 16^A of which extend over onto and rest on the brick side walls 3 and 4 throughout the length of this retort, while the two opposite end floor 25 plates 16^B of this retort extend over and rest on the brick end walls 5 and 6, and thus rest on the walls all around the retort furnace, as shown in Figure 2.

As seen in Figs. 10, 11 and 12, the opposite 30 sides 16^A of these floor members 16 of the retort 2 are provided with raised lugs 18^A that define bearing surfaces 21 on the extreme ends of these plates and the ends of the sides 18 of the cap member 17 are 35 provided with outwardly projecting lugs 22, which rest on the bearing surface 21 of the floor plate, up against the raised lugs 18^A of the floor plate 16, and bolt receiving holes 22^A are formed through both 40 of these lugs, and this cap and the floor plate are made to form one complete ore or oil shale roast converting retort section of the lower retort 2, which is made preferably eight inches in height by three feet 45 in width inside measurements.

The upper surface 17^A of the cap member 17 of this retort 2 is used to form the floor portion of the heat and smoke flue 13, and for this purpose it is provided with 50 stepped bearing surfaces 22^B at its opposite ends adjacent to defining lugs 22^C, on which rest the lower ends of the sides 13^B of the flue casing 13, which lower ends are 55 provided with outwardly extending lugs that are provided with bolt holes that are in alignment with the bolt holes 22^A in the cap and floor member of the retort 2. This flue consists of an enclosed cap member 23 and the sides already referenced, and it 60 is preferably of the same height and length as the retort 1 and is consequently of about the same area.

The upper surface 23^A of the flue 13, is 65 arranged to form the floor member of the retort 1, and its opposite sides 24 are pro-

vided with stepped shouldered bearing surfaces 25, on which the lower ends 26 of the sides 27 of the cap member 28 of the retort 1 rest. These lower ends 26 are provided with outwardly projecting lugs 28^B, that 70 rest on the bearing surfaces 25, and these lug bearing surfaces are provided with bolt receiving holes 30 that are in alignment with the bolt holes 22^A in the cap and floor members of the retort 2. 75

The cap member 28 of the retort 1 is of the same height as the cap member of the retort 2, and consequently the two retorts are of the same height and length. 80

The upper side surface 28^A of the top portion and of the cap member 28 of the retort 1 is arranged to form the floor member of the upper heat and smoke flue 15, the cap 33 of which rests on shouldered bearing surfaces 34 formed on the opposite sides of the floor surface 28^A of the cap 28 of the retort 1, and the lower ends of the side 35 of this smoke cap 33 are provided with projecting lugs 36, in which bolt holes 37 are formed that are in alignment with the bolt holes in the retort 1 and flue 13 and the retort 2, and a long bolt is inserted through the holes in these lugs, and it is tightened up to clamping 90 securely these two retorts 1 and 2 and their flues 13 and 15 tightly together. 95

The enclosed cap member 17 of each section of my tunnel shaped retort is provided with vertically positioned side flanges 39, at its opposite ends, which are machine finished to give them true smooth surfaces, 100 which sections are fitted air tight together and thus bolted together through these flanges to make a continuous tunnel-shaped retort, which may thus be made of any predetermined length, but as illustrated, forms a retort of six sections of about thirty feet in length, and as I employ two of them, the ore or oil-shale travels sixty feet in the two retorts, illustrated. 105

The floor plates 16 and their cap members 110 17 are secured together to form a continuously even, smooth, flat floor surface from one section to the other, throughout the length of each retort, and the opposite ends of the abutting sections of each retort are provided with overlapping stepped joints, which consist of the shouldered and tapered meeting surfaces 40 and 41, shown in Figures 10 and 11, and when the sections of each retort are bolted together lengthwise, they tighten up 115 into horizontal alignment and form a long tunnel form of retorts which are air tight all around, and each has a smooth straight floor for the crushed ores or oil-shales to be moved over through the length of each retort from the ore or oil-shale feeding machine 42, at the rear end of the retort through it to the forward end 42^A, where it falls into a chute 43 that is secured to one open end of the 120 front end of the heat and smoke flue 13, the 125 front end of the heat and smoke flue 13, the 130

open end of which it closes, and then through the retort 2 to a little beyond its end 44, where it drops into a screw conveyor 45, which extends across the end B of the retort 2 at substantially right angles to it. This screw conveyor 45 consists of a semi-circular trough member 46 that sets down into the rear end wall 6, and that fits up against the underside of a housing casting, the base 47 of which forms a short even continuation of the floor member 16 of the retort 2, and the trough of the screw conveyor is secured to its under side by angles 48.

The opposite ends of the trough 46 contain hubs 49, in which a shaft 50 is journaled, and the screw 45 is mounted on and secured to this shaft. The trough extends beyond the side of the brick wall of the retort furnace, and its end is closed, and its underside 20 at the outer end is provided with a downwardly extending discharge spout 52.

The end 53 of the shaft extends far enough beyond the adjacent hub of the trough to receive a sprocket wheel 54, which 25 is connected to and is rotated by a sprocket wheel 55, that is secured on a shaft 56, that extends through the power driven cone pulley 57 of the variable speed power transmission mechanism that operates to movingly 30 feed the crushed ore or oil shale through the two retorts of my multiple retort furnace.

The mechanism I employ for feeding crushed ores or oil-shales continuously through the two retorts is simple in construction, and it is also new and of novel character.

It consists of two link and roller type of chains, having cross bar ore moving and rabbling blades between the links of the two 40 chains, and the rollers of the links run on tracks placed on the opposite inside surfaces of the sides of the retorts 1 and 2. The rollers 58 are pivotally mounted between the overlapping ends of each pair of links 59, 45 and these rollers rest and run on a track 60, that consists of inwardly projecting lugs 60 that are cast on the inside surfaces of the side members of the retorts 1 and 2 at a short 50 distance above the floor members of these retorts.

The inside link of each pair of links throughout the length of the conveyor is provided with an inwardly projecting lug 62, to each of which the opposite ends of 55 cross bars 63 are secured. These cross bars consist of wide strips of sheet steel, enough of one end 63^A of each of which is bent at right angles to the width of the bars to enable them to be riveted or otherwise secured 60 to the lug 62. The lower portion of these cross bars forms the ore or oil shale moving and rabbling blades 64, and the lower edge portion of each blade is provided with a row of holes J through it which are placed at

about three-quarters of an inch above their 65 extreme lower edges and at preferably about two and one-half inches apart across the length of each blade. I preferably, however, place these holes J in each alternate blade in staggered relation to those of the other 70 blades on each side of it.

These holes J through these blades act to cause a certain amount of the ore that forms the top portion of the bed of ore that is being fed through the retorts by the 75 blades to flow through these holes and thus greatly assists in a stirring and rabbling action of the blades on the ore, which enables the heat to more thoroughly penetrate the ore on the floors of the retorts from its bottom to its top, no matter whether it is being run one-half or three-quarters or an inch or an inch and one-half or two inches deep.

The cross bars, which is a term I apply 80 to the upper edge of these blades, are secured to the lugs on the inside links to project upwardly and also downwardly, the blades on each alternate lug and link projecting downwardly, and the blades on the intermediate lug and link projecting upwardly, in order that as the endless conveyor 85 travels through the retort 1 all of the blades on the lower side of the conveyor, as shown in the cross sectional view of the retort furnace in Figure 1, will extend down close 90 to the floor of this retort and will move and at the same time rabble the crushed ore or oil shale to the opposite or front end A of the retort 1, then as the conveyor passes over the sprocket wheels at the end A of the retort 1, the blades on the other side or top 95 side of the conveyor that projected upward as it passed through the retort 1 will pass to the top side of the conveyor as it passes through the retort 2, and the blades that were on the top side of the conveyor as it 100 passed through the retort 1 will extend down to and move the ore and oil-shale along the floor of the retort 2 to its discharge end, from which it discharges into 105 the screw conveyor 45.

On the opposite ends of the blade portion 110 of these cross bars I place guard plates 66, and I preferably place them on every third blade of the blades that project from one side of the conveyor, and also on every third blade of the blades that project from the other side of the conveyor, as shown. These 115 guard plates 66 consist of short right-angled pieces of steel, the inner ends of two of which are riveted back to back to opposite sides of the blades, and their front ends form flat slidable surfaces that move along between the adjacent edges of the tracks and thus hold the links and rollers onto the 120 tracks against accidental displacement, and their exterior outer ends are bent inwardly 125 to prevent them from catching on the edge

of the tracks or on the sprocket wheels that support the conveyor as the links and roller chains pass around and over them.

The crushed and dried ore or oil-shale is fed into the retort 1 by means of a feeding-in machine 42, which is secured to the top of the housing casting 69. This feeding-in machine 42 consists of a hopper 68 that receives crushed and dried ores and oil-shales 10 through a conveyor from these ores or oil-shales crushing and drying machinery, which I do not illustrate, as any of the machinery at present in use for crushing and drying ores can be used for this purpose.

15 This feeding-in machine is provided with a body 70, in which a rotary feeder is mounted, that is arranged to feed the crushed and ground ore or oil-shale through it into the retort 1 without allowing any air to pass 20 through it with the ore. This feeding-in machine is operated by sprocket wheels 71 and 71^A and a sprocket chain 72. The sprocket wheel 71^A is mounted on a shaft that forms a part of and is rotated by the 25 variable speed transmission mechanism that operates the conveyor of the retort furnace.

The upper end of this housing casting 69 is provided with a spouted chute member C that conveys the ore or oil-shale from the 30 bottom of the feeding-in machine into the rear end B of the retort 1, where the moving and rabbling blades of the link and roller conveyor engage it and movingly feed it along the bottom of the floor of the retort 35 1 to its front end A, where it falls through the chute 43 and drops into and onto the floor 16 of the retort 2, along which the conveyor moves it to its discharge end, from 40 which it falls into the screw conveyor 45, that conveys it beyond one side of the retort furnace.

The ore or oil-shale conveyor moves continuously in a forwardly feeding direction that movingly feeds the ores and oil-shales through the retorts from their feed-in end to their discharge end. It does not reciprocate in the retorts, as some conveyors in this type of retorts do, but it keeps the ore or oil shale moving continuously forward through both retorts, and this steadily forward movement increases the converting treatment capacity of my retort.

The opposite ends of the conveyor are 55 wound on sprocket wheels 71^B and 72^B at the rear ends B, of the retorts, and on sprocket wheels 73 and 74 at the front end A of the retorts.

60 The conveyor is moved longitudinally through the retort 1 and then the retort 2 by a multiple cone and gear power receiving variable speed promoting and transmitting mechanism, the preferred construction and arrangement of which is as follows:

All of the sprocket wheels that support 65 the opposite ends of the conveyor are secured in pairs at proper distances apart to engage the link and roller chains on the opposite sides of the conveyor, and these sprocket wheel supporting shafts are rotat- 70 ably journaled in housing castings 69 and 75, which extend over the opposite ends A and B of the retorts and flues and are secured to them.

The housing casting 69 is secured to the 75 rear end B of the retorts 1 and 2 and the flues 13 and 15, and its lower end rests on top of the rear brick wall 6, and extends up to the top of the heat and smoke flue 15.

The two sprocket wheels 71^B that drive 80 the conveyor are secured at the right distance apart to enter the link chain between the side links and between the rollers of both link chains of the conveyor on a shaft 76, that extends across the housing casting 69 85 and through hubs 77 that are cast on its opposite outside surfaces, so that the link chain of the conveyor is driven in straight alignment through the retorts, and they are positioned at the proper height to cause its 90 rollers to enter the retorts quickly and to engage and run on their tracks, and to allow the rabbling blades to enter them close to their floors.

The housing casting 69 is provided with 95 a front plate portion 69^A that fits against and closes the open end of the flue 13. The upper end of the housing casting 69 is provided with a crushed ore or oil shale feeding-in chute 78, which extends from the 100 oven with the top of the upper heat and smoke flue 15, down past its rear end B against which it bears, and completely covers and closes it, and it enters by means of a spout discharging end 78^A into the 105 rear end of the retort 1, into which it discharges the crushed ore and oil shale from the feeding-in machine 42, which is secured on top of the feed inlet of the top of the housing in position to discharge the crushed ore or oil shale that is fed into its hopper 68, through a suitable conveyor from the crushing and drying machinery, all of which I do not illustrate, into the ore and oil shale receiving inlet of the spout of the 110 housing casting 69.

On the outside end of the shaft 76, a large gear wheel 78^B is secured, which meshes with a pinion 79 on a shaft 80^A having a large gear wheel 80. The shaft 80^A is journaled in bearings 81 formed on a bracket 82 that is secured to the end of the housing casting 69, and this gear 80 meshes with 120 and is driven by a pinion 83, that is secured on the shaft 56 which is mounted on bearings 85 formed on this bracket 82, and the cone pulley 57 is mounted on and secured 125 on this shaft 56. A small endless belt 87

encircles loosely the cone pulley 57, which is engaged by an opposite cone pulley 88. The cone pulley 88 is secured on a shaft 89 that is mounted on bearings 90 that are 5 formed on this bracket 82, and this cone pulley 88 engages and clamps the small endless belt 87 against the surface of the cone pulley 57 and causes the endless belt to rotate the cone pulley 57 by frictional contact with it. The shaft 89, on which the cone pulley 88 is secured, is journaled in vertically positioned bearings 90, which are provided with oblong apertures 92 that have straight sides, in which an oblong bushed 10 sleeve 92^a that is provided with a confining flange 93 on their inner ends, is vertically adjustable by means of a set of screws 94 and steel and leather disks 95 and 96 and steel slugs 97, which are mounted in apertures drilled down through the top portions of these bearings to bear against the tops of each of the bushed sleeves to adjust them and give to them a slightly yielding resilient movement to the shaft 89 and to the cone 88. 15

The shaft 89 extends beyond one side of the bracket, and a belt pulley 98 is secured on it, which receives rotative power by means of a belt from a power rotated pulley, which I do not illustrate. The belt 87 is provided with a manually operating belt shifter 98^b, which consists of a rod 98^c that extends diagonally from an aperture 98^p in the bracket across the length of the lower cone pulley 57, to another aperture 98^e in 20 said bracket 82, and on it a sliding sleeve 98^f is slidably mounted, which can be secured at any part of the length of the rod 98^c by a butterfly set screw 98^g that extends through the sleeve against the rod. 25

The belt shifting sleeve is provided with flanges 98^h on its opposite ends, which are pointed and extend close to the meeting surfaces of the cone pulley, and these flanges straddle the short endless belt which runs 30 or rotates between them, as the top cone presses this belt down onto the surface of the lower cone, and rotates it by frictional contact with it. 35

The automatically operating mechanism that tightens the conveyor and keeps it taut is preferably constructed as follows:

The two sprocket wheels 73 are secured on a shaft 99 at suitable distances apart to operatively fit between the rollers of the link roller chains, and the shaft 99 is journaled through the opposite sides of this housing casting 75, and also through hubs 100 that are cast on the opposite outside surface of this housing casting 75. 40

The two lower sprocket wheels 74 and their shaft 102 are arranged to be automatically moved laterally by weights 103, which are positioned to adjust the tension of the endless conveyor on its tracks and 45 sprocket wheels.

The preferred construction of this mechanism for maintaining an automatically adjustable operative tension on the ore or oil shale moving and rabbling conveyor is as follows:

On the outside surfaces of the housing, slightly raised boss portions 104 are cast, on the opposite side edges of each of which two narrow projecting lugs 105 are cast, and on the bosses between the lugs, long flat blocks 106 are slidably mounted and are held slidably between the lugs 105, by two thin strips of metal 107, which are secured by screws 108. The top surfaces of the strips extend over the adjacent side edges of the blocks, thus holding the blocks 106 slidably in their slideway between the lugs 105. Each one of these two blocks has an outwardly projecting hub 109, through which the opposite ends of the shaft 102 are journaled in babbitted bearings 110 formed in these hubs. The ends of the shaft also project through the blocks, and loosely through oblong apertures 111 formed through the raised bosses and the opposite sides of the housing casting. 50

On the under side of this housing casting 75, bearings 112 are secured in which a shaft 113 is journaled, and it extends far enough beyond the opposite ends of the housing casting 75 to receive and be secured to the pivotal centers 114 of two rock arms 115, the short arm 116 of which is pivotally secured to one of the two lugs 117 that are formed on the sliding blocks 106. The long arms 118 of these crank levers have pivotally connected to their ends one of the ends of the rods 119, the opposite ends of which are arranged to receive weights 103 to move the sprocket wheels and their shaft and the sliding blocks laterally away from the adjacent ends A of the retorts 1 and 2, to keep the conveyor in a straightened-out position on its tracks and sprocket wheels. 100

In the end of the housing casting 69 I place a door 121 that opens into the rear end B of the retorts 1 and 2, and in the front end of the housing casting 75, I place two doors 122 and 123. The doors 121 and 122 are large enough to enable the conveyor and its supporting and operating mechanism to be inspected and repaired when necessary, without removing the housing castings 69 and 75 from the ends of the retorts 1 and 2. 115

The door 123 opens into the end of the flue 15. All of these doors are provided with screw pressure clamping swing bolts 124 and lock blocks 125, which are arranged to clamp the doors with air tight joints against the housing castings. 120

One side of the upper retort 1 and of the lower retort 2 is preferably provided with two valve controlled air inlet pipes 127, which are placed at several feet apart, from the middle portion of this lower retort to 130

adjacent to its front end; and the upper retort 1 is also provided with one valve controlled pipe 128, which is placed between the middle of the length of this retort and its front end. Both retorts are provided with gas outlet pipes 129 and 130, which are placed in their rear end portions.

In order to recover the oil and the ammonium sulphate and other products from oil shales, I connect to the gas outlet apertures 131^A and 132^A of each of the retorts 1 and 2 a gas receiving and conveying vertically upward extending set of pipes 131 and 132, the lower ends of which are provided with flanges 133, which are bolted over the gas outlets and to the sides of the retorts 1 and 2. The pipes 131 and 132 are placed on opposite sides of the retorts 1 and 2, and I place in them on their opposite sides to their connection with the retorts' outlets plugs 133^A, in each of which a reduced nipple 134 is threaded, and to each of which a globe valve 135 is connected and a union 136 is connected to each valve by a nipple 137. An elbow 138 is threaded to each union by a nipple 139, and a steam inlet pipe 140 is threaded at its lower end to each of the elbows of the lower gas outlets of the lower retort 2 and by a T-fitting 141 to each of the valves that control the steam inlet portion of the gas outlet portions of the retort 1, and the opposite ends of these two steam inlet pipes, which are on the opposite sides of the retorts 1 and 2, are extended to and connected to a supply of steam under pressure, and the steam furnished by these pipes flows into the retorts, as well as into the pipes 131 and 132.

When steam is admitted into these retorts it is preferably admitted intermittently, and also intermittently, of course, into the vertical conveying pipes that carry the gases from the retorts and also the steam over into the oil and ammonium sulphate precipitating tanks; but it may be desirable at times to admit a little steam constantly for quite long periods of time, especially as these outlets are large enough to allow the air pressure which is admitted to the opposite ends of the retorts to drive the gases out of the retorts at the same time that a little steam is entering, but as a rule both the air and the steam are admitted at predetermined intervals when the oil shales are in just that right character of a conversion that the oxygen and the steam will mix with certain chemical elements contained in the shales.

The air and the steam when admitted at the proper time and in proper quantities form chemical unions with certain chemical elements in the oil shales that assist in disintegrating the oil shales and liberating their volatile elements, and also when the steam flows up into and through the pipes 131 and

132 it forces the gases through these pipes into the oil and ammonium sulphate precipitating vats.

The vertically upward extending gas receiving and conveying pipes 131 and 132 have threaded openings at their lower ends, which are closed by a plug 142 which can be removed to allow any sediment settling in these pipes to be discharged from them. The upper ends of these pipes 131 and 132 are provided with inwardly inclined terminal end portions 143, which terminate in collar portions 144 to which one of the ends 145 of two pieces of pipe 146 are threaded, the opposite ends of which are threaded to lugs 147 that have curved flanges that saddle inlet apertures formed on the opposite sides of a large pipe and are bolted to it. This large pipe 148 is of enough larger area than the two pipes 131 and 132 to receive all of the gases that flow into and through those pipes from the retorts 1 and 2. The end of this large pipe 148 that is adjacent to its inlet pipes at the rear end of the furnace is closed by a cap 149, but its opposite end, has connected therewith a pipe 149^A which contains a valve VV, which extends to and is connected to a blower or to an air pump 150, and from this blower or air pump an extension of the same sized pipe extends to and is secured to the closed top end of a condensing and precipitating vat 152.

In the main sectional elevation of my retort furnace I have only shown one gas outlet in the upper retort and one gas outlet in the lower retort, but in Figure 18, a plan view looking down on top of the retort is shown in which the main gas conveying pipe 148 is shown extending from the rear end of the retort furnace throughout its entire length to close to its front end, and in this view six different downwardly extending gas pipes are shown on each side of the main pipe, and these six gas pipes on each side of the main pipe 148 extend to gas outlet holes formed in the opposite side of the retorts 1 and 2 so that while I have preferably described the gas outlet and conveying pipes to the oil and ammonium sulphate recovery tanks, nevertheless, if desired, as many more up to six on each side may be employed, if desired.

The operation of my multiple retort furnace is as follows:

The ores or oil shales to be roastingly converted as a step in the recovery of their valuable products are first crushed to a fineness of from 10 to 40 mesh and are then dried and are conveyed dried to the hopper of the feeding-in machine of my retort furnace. Ores carrying platinum, gold, silver, copper, lead, zinc and other metals must be roastingly converted by themselves, and

oil shales must be roasted by themselves; that is, ores and oil shales should not be mixed together. The ores are fed automatically and continuously through the retorts by the conveyor mechanism, which is driven by the variable speed power receiving and transmitting mechanism; which gives to the operator different ore feeding time movements to the conveyor and consequently to the movement of the ores through the retorts.

The peculiar character of treatments that I give to ores after the roast converting treatment will be fully described in my new metallurgical process, which will be made the subject of another application for a patent, which is especially adapted to the recovery of platinum, gold, silver, copper, lead and zinc, bismuth, potash, magnetic iron, antimony, molybdenum, quicksilver, uranium, nickel, cobalt, ammonium sulphate, arsenic and other valuable metals, elements and products.

In operating my converting retort furnace for the treatment of custom ores or oil shales in a mining district, different speeds of the conveyor are necessary to give to different characters of ores or oil shales the time treatment necessary to properly convert them; but when my retort furnace is used for converting the ore from one mine, or the oil shale from a deposit, the conveyor speed can be set, and not changed from that time required in treating the ore from that mine or the oil shale from a particular district, as long as the character of the ore or the oil shale does not change, and the speed of the conveyor to move the ore or oil shale through the retorts is fixed to that particular time required in which to thoroughly roastingly convert the ores or oil shales. The time required to roastingly convert ores is determined by small tests made in assay furnace dishes that hold about one or two teaspoonsfuls, as the time required to convert that amount of ore in an assay retort is the same as the time required to treat the ores or oil shales in tonnage lots in my retort furnace.

If a retort furnace is built exclusively for treating ores, the gas outlets 129 and 130 are closed by flat plates 129^A, which are bolted to the outsides of the retorts over these outlets, and a row of holes AA is formed through the top of each of the cap members 17 and 28 of each section of the retorts 1 and 2 to allow the volatile gases that are liberated from the ores to flow into the flues 13 and 15 from the ore treating chambers of these retorts and through these flues to the chimney, and through the chimney to the atmosphere.

The gas outlet apertures in the cap members are shown in Figures 1, 5, and 7, but when a retort furnace is constructed and

is to be used exclusively for converting oil shales, the cap members of retorts 1 and 2 do not have any gas escaping apertures through them but are made solid and imperforate, as shown in Figure 13. Then all of the gases liberated from oil shales flow out of these retorts into the pipes 131 and 132 and to the oil and ammonium sulphate precipitating or condensing vats.

The valves of the valve controlled gas outlets of the retorts consist of a cast iron plate A¹, having a lug A² cast in its top portion to which the inner end of a valve rod A³ is secured, and the outer end of this valve rod extends through the adjacent side of the flues 13 and 15, and its outer end is provided with a handle A⁴. The valve A² is of a length to hold the valve plate A¹ over the gas outlet apertures AA and close them when the handle is positioned in against the outside surface of the flues; and when the valve rod is pulled out until the valve plate A¹ strikes against the inside surface of the flues the gas outlet apertures AA in the top members of the retorts are wide open. This arrangement in this co-operating ore or oil shale custom work treating retort furnace enables all of the conditions to be met that are required to give the very best results in treating either ore by itself or oil shale by itself in one retort furnace.

My multiple retort furnace of this present application embodies all of the preferred features of a number of years of careful experiments and practical experience in treating ores and oil shales that I have found necessary at this time to assemble into a new type of construction and arrangement into a multiple retort furnace, which I have herein illustrated; and it is the culmination of about 30 years of practical ore-treating metallurgical work, material evidence of which can be found in numerous patents that have been issued to me within that time, of which Patent No. 1,299,661 was the last to issue; and Serial No. 359,435, filed May 12, 1919, and Serial No. 359,538, filed February 17, 1920, are still pending in the Patent Office. While I have illustrated and described the preferred construction and arrangement of my present retort furnace, I do not wish to be limited to the construction and arrangement shown, as many changes might be made in it without departing from the spirit of my invention.

Having described my invention, what I claim as new and desire to secure by Letters Patent, is:

1. In a roasting furnace, a retort and flue comprising a pair of channel members so arranged that the web of one channel member cooperates with the side flanges of the second channel to provide a longitudinal passage, a plate cooperating with the flanges of said first channel to provide a second

- longitudinal passage, and means for delivering a material to be treated and a heating medium, respectively, to the said passages.
2. In a roasting furnace, a plurality of channel members superposed, the webs of the several members closing the openings of adjacent channel members whereby a plurality of superposed longitudinal passages are provided, and means for delivering a material to be treated and a heating material, respectively, to alternate passages.
3. In a roasting furnace, the combination of a pair of superposed retorts, the lower retort comprising a base plate, a channel member mounted thereon to define a rectangular retort, a second channel member mounted on said first channel to define a rectangular flue, and a third channel superposed on said second channel to define an other retort.
4. The structure as in claim 2 characterized by the fact that all of the members are held in substantially air-tight engagement by a common clamping means.
5. The structure as in claim 2 characterized by the fact that the sides of the channel members defining the retorts carry tracks for supporting an endless conveyor.
6. In an ore and oil shale furnace, the combination of two horizontally arranged superposed retorts, a pair of parallel tracks in each retort, and an endless conveyor, said conveyor comprising supporting means resting on each track, cross-members secured to said supporting means, each cross-member having means for advancing the material under treatment, and guide fingers on the edges of the cross-members for rubbing engagement with the sides of the tracks.
7. The structure as in claim 6, wherein the cross-members have openings near their outer edges to allow some of the material being roasted to pass therethrough.
8. The structure as in claim 6, wherein the cross-members have openings near their outer edges to allow some of the material being roasted to pass therethrough, the openings in adjacent members being offset with respect to each other.
9. In a roasting furnace, the combination of a pair of superposed retorts each provided with a heat conveying flue below and above it, and each provided with a valved controlled outlet in its top web leading into its upper heat conveying flue, said lower retort comprising a base plate, a channel member mounted thereon to define a rectangular retort, a second channel member mounted on said first channel member to define a rectangular flue, a third channel member superposed on said channel member to define a second retort and a fourth channel member superposed on said second retort to define a second flue over the top of said second retort; and means for attachably and de-
- tachably securing said retorts and their flues in vertical alignment together; a foundation for supporting said retorts and their flues, means within said foundation for producing heat and conveying it along the bottom of the base plate of said lower retort; a by-pass flue for conveying the heat from the foundation flue to the flue between the lower and the upper retort and a by-pass flue for conveying the heat from the flue between the retorts to the flue above the upper retort and a damper controlled chimney at the end of the upper flue.
10. In a roasting furnace, the combination of the foundation walls; heat producing means within said walls, two roasting retorts, one above the other having a flue between them and a flue and chimney above the upper retort, said retort and flues being secured together and resting on said foundation walls, by-pass flues through from said foundation walls into the rear end of the flue between the retorts, by-pass flues from the opposite end of the flue between the retorts into the flue above the upper retort; means for feeding ore or oil shale in to the upper retort, and means including a continuously feeding variable speed link belt roller chain conveyor mounted in said retort for feeding material continuously forward through said upper and lower retort in successive order in different periods of time.
11. In a roasting furnace, the combination of supporting walls and heat developing means, a channel shaped retort resting on said walls and receiving heat from said heat developing means, a rectangular flue forming casing secured to the top web member of said lower retort and arranged to form a rectangular heat conveying flue thereon jointly with the web of said lower retort; a second rectangular casing secured to the top web of said second flue and adapted to form a roasting chamber thereon, and a third flue casing secured on the top of the second retort and adapted to form a heat conveying flue along the top of said second retort, said web members of said lower and upper retorts being provided with valved controlled apertures, the valves of which are operated from the outside of said furnace and valve controlled air or steam inlet pipes extending through the sides of said retorts into the roasting chambers of said retorts.
12. A multiple retort roasting furnace, consisting of two retorts provided with open ends and placed one above the other and provided with a heat conveying flue between them, and a heat conveying flue and stack over the top of the upper retort; said retort and their flues being supported on a foundation containing heat producing means, and a heat conveying flue within said foundation under said lower retort; track mem-

bers on the inner opposite sides of each retort, means including a hopper for feeding ore into one end of the upper retort, means including an endless link belt roller chain conveyor arranged to run on said tracks in said retort and extending around the open ends of said retort, a hood extending over the open ends of both retorts at the opposite ends of said furnace, shaft-supported sprocket wheels mounted in each hood and rotatably supporting said endless link belt conveyor, bars extending from one chain to the other across each retort, and blades on

said bars arranged to move roasting material through both retorts from their feeding in ¹⁵ end to the upper retort to the discharge end of the lower retort, said blades being provided with apertures along their edges, arranged in the blade in alternate order, and means including belt driven pulleys and ²⁰ gearing secured to the shaft of one of said link belt conveyor sprocket wheels for imparting different predetermined speeds to said conveyor.

In testimony whereof I affix my signature.
ARON MILLS BEAM.
